UNITED STATES PATENT OFFICE.

DAVID HINDAHL, OF CHICAGO, ILLINOIS, ASSIGNOR TO RODGER BALLAST CAR COMPANY, OF CHICAGO, ILLINOIS, A CORPORATION OF MAINE.

SELECTIVE DUMP CAR.

Application filed July 3, 1924. Serial No. 723,862.

The present invention relates to selective dump cars.

More particularly the present invention relates to cars for depositing ballast along a railroad track either between the rails, at one side of the rails, at the other side of the rails, or in any desired combination of said regions of dumping. It is common to deposit ballast from a moving car, and for this purpose cars have been provided having dumping mechanism for permitting a flow of ballast to the region between the rails and for permitting a flow of ballast outside of the rails. The ballast cars are frequently operated in trains, and when one car has deposited its ballast the operator will control another car to start the flow of ballast.

In ballasting track simultaneously to the center and sides, conditions sometimes arise in which it is desirable to suddenly increase the amount of flow of material to the side, while at the same time maintaining a uniform flow of material to the center of the track.

An object of the present invention, therefore, is to provide dumping mechanism which will permit the relatively uniform flow of ballast to the region between the rails, while permitting a quick increase through wide variations of the flow of ballast to either or both sides of the rails.

Further objects will appear as the description proceeds.

35 Referring to the drawings.

Figure 1 is a transverse sectional view of a railway dump car embodying the principles of the present invention, showing the dumping mechanism in position for permitting the flow of ballast to one side of the rails upon which the car is mounted;

40 Figure 2 is a view of the structure shown in Figure 1 but with the dumping mechanism in position to permit flow of ballast to a region between the rails;

45 Figure 3 is a fragmentary view illustrating mechanism for controlling the flow of ballast to regions outside the tracks; and

50 Figure 4 is a view of the structure shown in Figure 3 but taken along a plane at right angles to the view shown in Figure 3.

The numeral 1 indicates a railway dump car having the side walls 2-2. Extending longitudinally of said car are the center

sills 3-3, which are provided with the cope 55 4, which divides and sheds ballast or other lading to the two sides of the longitudinal central plane of said car. Mounted adjacent to the sills 2-2 are the inwardly sloping bottom walls 5-5. Mounted in abutting relationship with the sills 3-3 are the outwardly sloping bottom walls 6-6. Each pair of walls 5 and 6 is controlled by a door member indicated by the numeral 7, each of which doors 7-7 is of compound construction, as will be more fully referred to hereinafter. Each of said doors 7-7 is pivoted for swinging movement about a corresponding longitudinally disposed axis 8, being pivotally supported by a corresponding hinge 60 plate 9. Figure 2 shows the doors 7-7 swung to open position whereby to permit the flow of ballast or other lading to the region between the rails. For the purpose of providing a relatively uniform adjustment of doors 7-7 for center dumping, certain link mechanism is provided, which is illustrated more or less diagrammatically in Figures 1 and 2 of the drawing. The numeral 10 indicates a shaft extending longitudinally of the car, which shaft has non-rotatably mounted thereon the crank member 11, having the two crank arms 12 and 13. The crank arm 12 is connected through the two short links 14 and 15 to the lever 75 arm 16, which is connected to the swinging extremity of the left hand door 7 as the parts are viewed in Figures 1 and 2. The crank arm 13 is connected through the links 17 and 18 with the lever arm 19, which lever arm 80 19 is connected to the swinging extremity of the right hand door 7. No novelty is claimed in the present application for the link mechanism by means of which the shaft 11 controls the doors 7-7. It will be understood that when the shaft 10 is turned in one direction the doors 7-7 will be gradually moved to closed position. Rotation with the shaft 10 in the opposite direction will result in the gradual opening of the doors 7-7. For providing the relatively slow adjustment of shaft 10, said shaft may be provided with a worm wheel 10^a non-rotatably mounted thereon, which worm wheel may derive its power from the worm 10^b, which worm is non-rotatably mounted on the cross shaft 10^c, which may be turned by any preferred means. The worm wheel 10^a, worm

10^b and shaft 10^e have been omitted from Figure 1 for purposes of clearness. The advantage of this relatively fine adjustment for dumping between the tracks will be clear, 5 inasmuch as the amount of ballast ordinarily required to be deposited between the tracks is quite uniform and inasmuch as care should be taken not to flood the rails. When one car after another of a train is to be 10 dumped, the fine adjustment permitted by the illustrated mechanism permits the operator or operators to start an easy flow of ballast to the region between the tracks at the time that the last portion of the ballast 15 is being deposited from another car of the train.

Each of the doors 7—7 is provided with a hinged intermediate closure 20, each of said closures being hinged along longitudinal axes 21—21. Said intermediate closures 20—20 are independently operable and control the flow of ballast laterally of the rails upon which the car is mounted. For the purpose of controlling the closures 20—20, 25 each of said closures is provided with a flexible connector 22, which extends over the swinging edge of the corresponding closure 20 and which is adapted to be wrapped up upon the corresponding longitudinally extending shaft 23. Preferably the pitch line of each chain 22 should extend through the axis 8 of the corresponding swinging door 7.

Figures 3 and 4 illustrate mechanism for controlling the rotation of either of the shafts 23 to control side dumping. Referring to Figure 4, it will be noted that the shaft 23 is provided with the ratchet member 25. Rotatably mounted upon the shaft 40 23 is the ratchet lever 26, which has pivoted thereto the pawl 27. The pawl 27 is adapted in certain positions of the ratchet arm 26 to engage the teeth of the ratchet member 25 and to communicate rotative movement to shaft 23. As shown in Figure 4, 45 the pawl 27 may readily be thrown out of operative engagement with the ratchet 25. Also mounted upon each of the shafts 23 is the ratchet plate 28 having teeth 29—29 50 projecting from the opposite faces thereof. Said teeth 29 have abutting faces 30 extending in planes substantially parallel with the axis of the shaft 23 and have beveled faces 31. Pivottally mounted adjacent to the shaft 23 is the bifurcated detent member 32, which detent member 32 has the socket portion 33 for the reception of a rod. Said detent member 32 is rotatably mounted upon the pivot 34 and is provided with the two 55 jaw members 35—35, which are positioned to embrace the edge portions of the ratchet plate 28. The teeth 29—29 and jaw members 35—35 are so coordinated that when the corresponding door 20 is being closed, 60 the beveled portions of the teeth 29—29

will cause the reciprocation of the detent member 32 about the pivot 34, permitting closure of said door 20. Cooperation between a jaw member 35 and the unbeveled face 30 of a tooth 29 will hold the corresponding door in the position to which it has been moved. When it is desired to permit the opening of the corresponding door 20, the detent member 32 may be oscillated about the pivot 34, whereby the corresponding door will be allowed to move rapidly in a step-by-step movement to the open position desired by the operator. It will be understood, of course, that after the ratchet lever 26 has moved the corresponding door 20 to the desired closed position, the pawl 27 may be moved out of cooperative relationship with the ratchet 25, whereby to permit the ready opening of the corresponding door 20 by means of the detent member 32. 75 80 85

It will be clear without detailed explanation that a dump car or a train of dump cars may be moved along a track at the required rate and that dumping may be controlled with relatively uniform adjustment for depositing the required amount of lading between the rails without flooding said rails. For depositing lading outside of the rails, where a sudden increase in the flow may be desired, the illustrated mechanism permits 90 the ready control of the flow through a relatively wide range, as required by the conditions along the track. 95

Though certain preferred mechanism for providing relatively fine adjustment for center dumping has been illustrated and though certain preferred mechanism for permitting rapid changes in the rate of flow for side dumping have been illustrated, it is clear that other mechanisms having these functions may be employed without departing from the spirit of the present invention. 100 105 110

What is claimed is:

1. In a railway dump car, in combination, means providing a pair of laterally disposed hopper bottoms, closures for said bottoms, means for operating said closures to permit dumping between the rails upon which said car is mounted, and means for controlling said closures to permit dumping laterally of said rails simultaneously with said dumping between the rails, said center dumping control means having a relatively uniform adjustment, said control means for dumping laterally of said rails being such as to permit rapid changes through a relatively wide range in the flow of dumpable material. 115 120

2. In a railway dump car, in combination, doors for discharging the load between the rails and doors for discharging the load outside the rails, operating mechanism for the doors discharging between the rails, said mechanism having a relatively uniform adjustment, and other operating mechanism 125 130

for the doors discharging outside the rails, said mechanism having a rapidly variable adjustment.

3. In a railway dump car, in combination, 5 side walls, center sills, means for dividing and shedding ballast to the two sides of said center sills, doors pivoted along axes adjacent to said side walls for delivering ballast between the rails upon which the car 10 is mounted, said doors being provided with intermediate closures for delivering lading outside of said rails simultaneously with the delivery of ballast between said rails, control means for said doors having a relatively uniform 15 adjustment whereby the flow of ballast between said rails may be nicely adjusted, and control means for said closures having a relatively rapid adjustment whereby 20 irregularities in the regions outside of said rails may be readily compensated for.

4. In a railway dump car, in combination, doors for discharging the load between the rails, doors for discharging the load outside of the rails, operating mechanism for the doors discharging between the rails, said 25 mechanism having a relatively uniform adjustment, and other operating mechanism for the doors discharging outside of the rails, said other operating mechanism including mechanism for controlling the opening of said last mentioned doors under the influence of the load within said car, said other operating mechanism also including ratchet mechanism for raising said last mentioned doors against the influence of gravity, 30 said ratchet mechanism being adapted to be rendered inoperative.

Signed at Chicago, Illinois, this 23rd day of June, 1924.

DAVID HINDAHL.
